Patented July 6, 1971

221,080

DENTAL ULTRASONIC UNIT

Morison S. Cousins, Plainview, N.Y., assignor to
Cavitron Corporation

Filed Oct. 10, 1969, Ser. No. 19,506

Term of patent 14 years

Int. Cl. D24—03; D7—06

U.S. Cl. D24—1

FIG. 1

FIG. 2

FIG. 3

FIG.4

FIG.5

FIG. 1 is a front elevation view of a dental ultrasonic unit showing my new design;

FIG. 2 is a rear elevation view of the dental ultrasonic unit;

FIG. 3 is a right side view of the dental ultrasonic unit;

FIG. 4 is a top plan view of the dental ultrasonic unit; and

FIG. 5 is a perspective view of the dental ultrasonic unit.

I claim:

The ornamental design for a dental ultrasonic unit, substantially as shown.
